TROLLEY CONTROLLING MEANS

George H. M. Dahl, Washington, D. C.

Original application October 5, 1939, Serial No. 298,104, now Patent No. 2,317,363, dated April 27, 1943. Divided and this application June 30, 1942, Serial No. 449,129

8 Claims. (Cl. 191—45)

My invention relates to trolley controlling means for toy electric railway street cars, commonly known as trolley cars, and it is an object of the same to provide improved means whereby the driving means for the car will change automatically from an overhead system to an underground system and vice versa, with means to insure that the trolley will engage its wire with safety and certainty.

Another object of the invention is to provide trolley controlling means, particularly adapted for use in a system of the kind referred to, in which the trolley will be moved through a wide arc by a small movement of its controlling means, and will be accurately held against rattling or chattering when in its inoperative position.

Other objects and advantages of my invention will appear from the following description and from the annexed drawings which are made a part of this application and in which similar reference characters indicate similar parts.

Referring to the drawings:

Fig. 1 is a side elevation of parts of a trolley controlling means, with parts in section.

Fig. 2, a top plan of parts shown in Fig. 1.

Fig. 3, a vertical section of parts shown in Fig. 1.

Fig. 4, a side elevation of part of a toy street car system, showing the car operating by means of a trolley and also operated by an underneath system.

Fig. 5, a top plan of parts shown in Fig. 4.

Fig. 6, a detail of parts shown in Figs. 4 and 5.

Fig. 7, an elevation, partly in section, of a car with a modified trolley controlling system.

Fig. 8, a partial top plan of the trolley car of Fig. 7, and

Fig. 9, a horizontal section of part of the car of Fig. 7.

In the drawings, the trolley and its operating mechanism include a rod 80 extending up through the floor of the car and provided at its lower end with a roller 81 in a yoke 82, held down yieldably by means of a spring 83 surrounding the rod and bearing against a collar 84 on the rod and also against the upper end of the yoke. At its upper end the rod 80 is pivoted at 86 to a bent lever 87 pivoted at 88 to a fixed upper part of the car. At its rear end the bent lever 87 is pivotally connected at 89 to the trolley pole proper 90. This pole has a flat-faced block 91' at its forward end adapted to rest on a fixed part 91 of the car when the pole is lowered, said block having a rocking and sliding movement upon the rear end of the frame 55

portion 91 to bring it into the position shown in dotted lines in Fig. 1.

A spring 92 connected to a pin 93 on the pole and to a fixed pin 94 tends to raise the trolley pole to bring the trolley 95 into operative position, in which it remains during normal operation of the car. A portion of an insulated third rail is shown at 96 in Fig. 5. The third rail may be at the middle of the track, or at one side thereof, as in subway cars. When the car reaches such a third rail the roller 81 rides up on it, forcing the rod 80 upward, and oscillating the lever 87 so as to cause its pivotal connection with the trolley pole to bring the pole down into the position illustrated in Fig. 1.

Such operation of the car and the trolley pole is indicated in Figs. 4 and 5, where the operation in an underneath system is indicated at the left in the figures and the ordinary trolley-controlled operation is illustrated at the right. It will be noted that an incline is shown at 97, down which the wheel 81 rides when it moves off the third rail, permitting the trolley to be raised by its spring to the position there shown.

In order to guide the trolley so as to insure that the wheel 95 will engage the trolley wire without fail I provide a guide with a flat top 99 which limits the upward movement of the wheel and with side portions 100, 101 approaching each other in the direction of movement of the car in Figs. 4 and 6, this guide being suitably supported as for example by means of a cross bar 102 and uprights 103. As the trolley moves along the guide it is forced to central position by the sides of the guide so as to engage the wire 98 correctly and without fail.

Figs. 7, 8, and 9 illustrate a modified form of automatic trolley operating means. In this form of the invention the trolley pole 104 is moved from the dotted line position wherein it engages the wire 105 into the position shown in solid lines, when underneath operation is indicated, by means comprising a cord or link 106 connected to a lever 107 pivoted at 108 and having pivoted thereto at its forward end a vertically movable plunger 109 carrying a wheel 110 at its lower end for engagement with the third rail.

It will be obvious to those skilled in the art that various changes may be made in the device of my invention, all without departing from the spirit of the invention; and therefore I do not limit myself to what is shown in the drawings and described in the specification, but only as indicated in the appended claims.

This application is a division of my applica-

tion Ser. No. 298,104, filed Oct. 5, 1939, now Patent No. 2,317,363, April 27, 1943.

Having thus fully described my invention, what I claim is:

1. In a toy electric street car system, a track including a pair of car supporting rails and a third rail between them, a car having a vertically movable rod mounted thereon, a roller at the lower end of the rod for engagement with said third rail, a lever mounted on a fixed part of the car and connected to said rod an overhead trolley pole pivoted to said lever, a cam positioned to raise said roller and place it on said third rail, and connections from the rod to said overhead trolley for lowering the trolley as said roller rides up said cam.

2. In a toy electric street car system, a track including a pair of car supporting rails and a third rail between them, a car having a vertically movable rod mounted thereon, a roller at the lower end of the rod for engagement with said third rail, an overhead trolley pole pivotedly mounted on said car, a cam positioned to engage said roller and place it on the said third rail, connections from the rod carrying the roller to said overhead trolley for lowering the trolley as said roller rides up said cam, means for raising the overhead trolley as said roller rides down said cam, and means for guiding the trolley to its wire including a trough-like guide closed at the top and having sides approaching each other in the direction of movement of the car.

3. In a toy electric car, a lever pivotally mounted on the upper part of the car, a trolley pole pivotally mounted on one arm of said lever, said trolley pole having a forwardly extending portion rockably and slidably engaging a fixed portion of the car body, spring means attached at opposite ends to said trolley pole and a fixed part of the car, said means tending constantly to raise the trolley pole, and means connected to the other arm of said lever for positively operating the lever to lower the trolley pole.

4. In a toy electric car, a lever pivotally mounted on the upper part of the car, a trolley pole pivotally mounted on one arm of the lever, said trolley pole having a forwardly extending portion rockably and slidably engaging a fixed portion of

the car body, means connected to the other arm of said lever for operating the lever to raise and lower said trolley pole, and a block at the forward end of said trolley pole, said block having an extended flat face on its under side arranged to rest on a corresponding flat face of the car body to provide a steady rest for said pole when lowered.

5. In a trolley car adapted to change from overhead to underground trolley service and vice versa, the combination of a car, an overhead current collector movably mounted on said car, a current collector movably mounted underneath said car, and connections between said collectors for automatically moving one of them to active position when the other is rendered idle and vice versa.

6. In a trolley car, a lever pivotally mounted on a fixed part of the car, a trolley pole pivoted at one end of said lever, means for either raising or lowering the trolley pole through a relatively large arc as the said end of the lever moves through a relatively small arc in either direction, a trolley underneath the car, and connections between said trolleys for moving the upper trolley to active position when the underneath trolley is rendered inactive and vice versa.

7. In a trolley car, a lever pivotally mounted on a fixed upper part of the car, said lever having a long arm and a short arm, a trolley pole pivoted at the end of the long arm, means to raise or lower the free end of the trolley pole through a relatively large arc as the said end of the lever moves through a relatively small arc, a trolley movably mounted underneath the car, and connections from the underneath trolley to the short arm of said lever for inactivating the upper trolley when the lower one goes into action and vice versa.

8. In a trolley car, a trolley pole upon the car, means tending constantly to elevate the trolley pole, a lever underneath the car, a plunger at one end of said lever, a roller on the plunger in position to engage a third rail when the plunger is elevated, and a cord connecting the other end of the lever to the trolley pole in such manner as to elevate said plunger when the trolley pole is lowered.

GEORGE H. M. DAHL.
